UNITED STATES PATENT OFFICE.

EDUARD SCHENK, OF SHERADAN BOROUGH, PENNSYLVANIA.

FLOOR-FINISHING APPARATUS.

No. 866,074.

Specification of Letters Patent.

Patented Sept. 17, 1907.

Application filed June 6, 1906. Serial No. 320,444.

To all whom it may concern:

Be it known that I, EDUARD SCHENK, a resident of Sheradan borough, in the county of Allegheny and State of Pennsylvania, have invented a new and useful Improvement in Floor-Finishing Apparatus; and I do hereby declare the following to be a full, clear, and exact description thereof.

This invention relates to surfacing machines such as abrading and polishing machines for finishing floors or 10 other surfaces.

The object of my invention is to improve the construction of machines of this character so as to render the same more efficient and easier to handle, as well as to simplify and reduce the cost thereof.

15 Many kinds of floors and other surfaces must be dressed off or polished to smoothen the same. My invention provides a machine for this purpose which is light, simple and easy to handle. It has been found by experience that in order to properly smoothen most 20 floors very little pressure should be applied to the tool, but the latter should merely skim over the floor. My machine is especially designed to give this useful result, and is so constructed that it can be handled with a minimum amount of labor so as to avoid the possibility 25 of throwing so much weight on the tool as to injure the surface being dressed.

The invention consists of details of arrangement and construction hereinafter described and claimed.

In the accompanying drawings Figure 1 is in part a 30 side view and in part a section of my machine on the line 1—1, Fig. 2; Fig. 2 is a plan view of the same; Fig. 3 is a front view of the head of the machine; and Fig. 4 is a detail section on the line 4—4, Fig. 2.

35 My machine comprises a suitable frame 1 preferably of skeleton construction, as shown, and having at one end, which I will term the forward end, a head 2 in which is mounted the vertical spindle 3, the latter at its lower end carrying the tool or tools. The upper end of the spindle is provided with a pulley, sprocket wheel 40 or the like, 4, which is connected by a belt 5 to a similar wheel 6 on the shaft 7 of an electric motor 8 mounted in the rear end of the frame 1. The machine is mounted on comparatively large wheels 10 which are journaled to the frame intermediate its ends and between the 45 head 2 and motor 8. The object of this is to, as far as possible, counter-balance the head 2 by the motor 8 so that the machine is very nearly balanced, and the tools will not be pressed upon the floor with too great a weight, and the machine as a whole can be much more easily 50 handled, as it will require only a slight lift on the handles 11 connected to the head 2 to move the machine around as is necessary when finishing the surface of a floor. The large wheels 10 render the moving of the machine exceedingly easy.

55 In order to preserve the counterbalance when different tools are used, or to alter the amount of weight with

which the tool bears on the floor, a suitable adjustment for the counter-balance is provided. This can be effected in any way, such for instance as mounting the motor 8 on the frame 1 so as to be adjustable toward and 60 from the journals of the wheels. Preferably, however, it is effected by adjustably connecting the axle 12 of the wheels to the frame 1, this being effected by means of U-shaped clamps 13 connecting said axle to the top members 14 of the side frames. It is obvious that by 65 moving the axle either forwardly or backwardly the counter-balance can be varied in any desired manner.

The motor 8 is actuated from lead wires 16 coming from any suitable source and the controlling mechanism for the motor, such as the switch 17 and rheostat 70 may be mounted on a plate 18 connected to the rear end of the frame 1.

With most machines of this character a single flat faced disk or cylinder is connected to the tool shaft 3. Such disks have a zone of no, or limited, movement at 75 the center thereof, which zone performs little or no work. In my improved machine I use a plurality of tools, two such tools 20 being shown mounted in a cross head 21 secured to the lower end of the shaft 3. The tools 20 have their spindles 22 freely rotatable in bearings 23 in the cross head 21 so that in the rotation of the shaft they are carried in paths of revolution and may also freely rotate on their axes. In this way the finishing tool has no zone which performs no or little work.

85 In all machines of this character it is the practice to provide suction apparatus for conveying away the dust or other particles removed from the floor. For this purpose I provide directly on the shaft 3 two or more blower or fan blades 25 which are within a hood 90 26 covering the tool and projecting close to the surface being finished. This hood has connected thereto one end of a conduit 26^a which leads to a dust receptacle 27 carried by the frame 1. In the rotation of the shaft 3 the blades 25 act as fans and blow the dust produced 95 through the conduit 26^a into receptacle 27. Said blades of course are so placed that they force the air upwardly into the conduit 26 instead of downwardly toward the floor.

The head 2 is adjustably secured to the frame 1 in a 100 manner to permit raising and lowering the head or to incline the shaft so as to cause the tool to bear on the floor with its full face, or only on a side. This is effected by providing horizontal slots 28 and vertical slots 29, one set in the frame member and the other in 105 the head member, together with suitable securing bolts 30. The vertical slots allow for raising and lowering the head 2 to accommodate various tools or for other purposes, while the horizontal slots permit the head to be swung to bring the spindle 3 to any desired inclination.

110 The machine described is simple of construction, of

minimum weight and efficient in operation. The counter-balancing of the tool head by means of the motor, as described, prevents any possibility of the tool bearing against the surface being finished with too great pressure so that danger of injuring the same is avoided. This counter-balancing of the machine also renders it very easy of manipulation as the operator need apply only very little force on the handles in order to move the machine around. The large wheels also are of decided advantage for this purpose.

What I claim is:

1. A portable surface-finishing machine comprising a frame, a finishing head on the front end of said frame, a motor on the rear end of the frame, a wheeled support pivotally connected to the frame between the head and motor, whereby the latter counter-balances the head, driving connections from the motor to the head, and a handle on the forward end of said frame for manipulating the machine.
2. A portable surface-finishing machine comprising a frame, a rotary finishing tool carried on one end of said frame, a motor on the other end of the frame, driving connections from the motor to the tool, a wheeled support pivotally connected to the frame between the tool and motor, whereby the latter counter-balances the tool, adjusting means for varying the counter-balance, and a handle on the tool end of the frame for manipulating the machine.
3. A portable surface-finishing machine comprising a frame, a finishing head on one end of the frame, a motor on the other end of the frame, a single pair of wheels connected to the frame between the finishing head and motor, whereby the latter counter-balances the head, means permitting adjustment of the wheels longitudinally of the frame in order to vary the counter-balance, and a handle on the head end of the frame for manipulating the machine.
4. A portable surface-finishing machine comprising a frame, a finishing head on the forward end of said frame, a motor on the rear end of the frame, driving connections from the motor to the finishing head, a single pair of large wheels constituting the sole supporting means of the machine when in use, an axle for said wheels secured to the frame between the head and motor and above the center of gravity of the latter, and a handle on the forward end of the frame.
5. A portable surface-finishing machine comprising a

skeleton frame, a finishing head on the forward end of said frame, a motor on the rear end of the frame, driving connections from the motor to the finishing head, a single pair of large wheels constituting the sole support of the machine when in use, an axle for said wheels secured to the skeleton frame between the head and motor, means for adjusting said axle longitudinally of said frame, and a handle on the forward end of the frame for manipulating the machine.

6. A portable surface-finishing machine comprising a frame, a vertical shaft mounted on the forward end of the frame and carrying a finishing tool at its lower end, a motor mounted on the rear end of the frame, driving connections from the motor to said tool shaft, a single pair of large wheels journaled to the frame between the tool shaft and motor and above the center of gravity of the latter and being the sole supporting means of the machine when in use, and a handle on the forward end of the frame.

7. A portable surface-finishing machine, comprising a frame, wheels upon which the same is mounted, a head secured to the frame by means permitting the same to be inclined from a vertical position, a vertical tool spindle rotatably mounted in said head, a motor on the frame, and driving connections from the motor to the tool spindle.

8. A portable surface-finishing machine comprising a frame, a single pair of wheels upon which said frame is mounted, a tool carrying head, means for securing the head to the frame so as to permit adjustment both vertically and at an inclination to the perpendicular, a vertical tool spindle mounted in said tool head, a motor mounted on the frame, a vertical motor shaft, and driving connections from the motor to the tool spindle.

9. A portable finishing machine comprising a frame, a head secured to the forward end thereof by connecting means permitting said head to be adjusted vertically and also inclined with reference to a vertical position, a vertical tool spindle rotatably mounted in said head, a motor on the opposite end of said frame, driving connections between the motor and tool spindle, and a single pair of wheels connected to the frame between the head and the motor.

In testimony whereof, I the said EDUARD SCHENK have hereunto set my hand.

EDUARD SCHENK.
